ATTORNEY.

UNITED STATES PATENT OFFICE.

ANGELINE SMELKER, OF NORTH STAR, OHIO, ASSIGNOR OF ONE-THIRD TO
MARY M. MEHIRING, OF INDIANAPOLIS, INDIANA.

DESIGN FOR A FRUIT-JAR.

SPECIFICATION forming part of Design No. 32,757, dated May 29, 1900.

Application filed April 28, 1900. Serial No. 14,764. Term of patent 14 years.

To all whom it may concern:

Be it known that I, ANGELINE SMELKER, a citizen of the United States, residing at North Star, in the county of Darke and State of Ohio, have invented and produced a new and original Design for Fruit-Jars; and I do declare the following to be a full, clear, and exact description of the same, reference being had to the accompanying drawings, forming a part thereof.

My invention relates to a new and original design for a fruit-jar; and the object is to provide a design of this character that shall be both useful and ornamental.

The invention consists in a jar composed of a body having a bottom provided with an annular recess surrounded by a rim in which are notches and an annular rim projecting above the top of the jar, which will be now described in detail.

Referring to the drawings, Figure 1 is a perspective view showing more particularly the upper portions of the invention; Fig. 2, a perspective view showing more particularly the lower portions, and Fig. 3 a vertical and diametrical sectional view showing more clearly the elevated and depressed portions of the jar.

Similar letters of reference refer to similar parts in the several views.

A designates the body of the jar, which is circular and somewhat larger diametrically between the bottom and top thereof; B, the bottom, having an annular rim C at the cir-

cumferential edge thereof extending as a portion of the body-wall below the bottom, which also has an annular recess D adjacent to the rim C. The rim C has notches E disposed at intervals about the lower edge thereof. At the top of the body A is an annular shoulder a, from which an ordinary neck J rises, the shoulder having a slight depression b at the base of the neck. The lid F and the retaining-ring are exhibited as though they were integral and are ornamental as well as useful parts of the whole design. An annular rim G extends above all other portions of the jar and has substantially a plane upper surface, and a flange I is in a lower plane, while the lid F is in a still lower plane. The whole top appears as a basin surrounded by the rim G, and the bottom presents itself as a disk in which is the recess D, surrounded by the notched rim C, and by the formation above described is exhibited the leading feature as a single design already indicated.

Having described my invention, what I claim is—

The design for a fruit-jar, as herein shown and described.

In testimony whereof I affix my signature in presence of two witnesses.

ANGELINE SMELKER.
